US0D1031820S

(12) **United States Design Patent** (10) Patent No.: **US D1,031,820 S**
(45) Date of Patent: ** Jun. 18, 2024

(54) **CAMERA MOUNT**

(71) Applicant: **Amazon Technologies, Inc.**, Seattle, WA (US)

(72) Inventors: **Thomas Burns**, Patchogue, NY (US); **Jonathan Howard Biddle**, San Francisco, CA (US); **Michael O'Connor**, Charlestown, MA (US)

(73) Assignee: **Amazon Technologies, Inc.**, Seattle, WA (US)

(**) Term: **15 Years**

(21) Appl. No.: **29/918,516**

(22) Filed: **Nov. 28, 2023**

Related U.S. Application Data

(62) Division of application No. 29/811,054, filed on Oct. 11, 2021, now Pat. No. Des. 1,012,160, which is a division of application No. 29/722,139, filed on Jan. 27, 2020, now Pat. No. Des. 933,118.
